(57) **CLAIM**

I claim the ornamental design for a nasal dilator, as shown and described.

DESCRIPTION

FIG. 1 is a perspective view of the nasal dilator of the present invention, shown positioned on a user's nose;

FIG. 2 is a top plan view of the nasal dilator shown in FIG. 1; FIG. 3 is a front elevational view of the nasal dilator shown in FIG. 2;

FIG. 4 is a right side elevational view of the nasal dilator shown in FIG. 2; and,

FIG. 5 is a bottom plan view of the nasal dilator shown in FIG. 2.

The broken lines showing the human face are directed to environment and are for illustrative purposes only; the broken lines form no part of the claimed design.
